Primary Examiner — Robert Delehanty

CLAIM

The ornamental design for a spout cover, as shown and described.

DESCRIPTION

FIG. 1 is a left side view of a spout cover showing my new design, a right side view being a mirror image thereof;
FIG. 2 is a rear view of the spout cover;
FIG. 3 is a front view of the spout cover;
FIG. 4 is a top view of the spout cover;
FIG. 5 is a bottom view of the spout cover; and,
FIG. 6 is a top front side perspective view of the spout cover. The broken line showing a spout is included for the purpose of illustrating environment that forms no part of the claimed design.
